UNITED STATES PATENT OFFICE.

CORNELIUS T. EVANS, OF AMERICUS, KANSAS.

MEANS FOR PRESERVING.

1,303,549.

Specification of Letters Patent. Patented May 13, 1919.

Application filed December 19, 1917. Serial No. 207,906.

To all whom it may concern:

Be it known that I, CORNELIUS T. EVANS, a citizen of the United States, residing at Americus, in the county of Lyon and State 5 of Kansas, have invented certain new and useful Improvements in Means for Preserving, of which the following is a specification, reference being had to the accompanying drawings.

- 10 This invention relates to certain improvements in preserving and it is an object of the invention to provide a means for preserving tubers such as sweet potatoes or other vegetables and it is an object of the 15 invention to provide a novel and improved means for preserving which includes a substantially inclosed housing in which are arranged receptacles for containing the vegetables or the like and which receptacles are 20 constructed in a manner to permit the passage of heat upwardly therethrough and wherein the lower portion of the housing is provided with a compartment to contain a heat generating unit.
- 25 The invention consists in the details of construction and in the combination and arrangement of the several parts of my improved means for preserving whereby certain important advantages are attained and 30 the device rendered simpler, less expensive and otherwise more convenient and advantageous for use, as will be hereinafter more fully set forth.

The novel features of my invention will 35 hereinafter be definitely claimed.

In order that my invention may be the better understood, I will now proceed to describe the same with reference to the accompanying drawings wherein:

- 40 Figure 1 is a view in elevation with a cabinet as embodied in my present invention;

Fig. 2 is a view in elevation of the cabinet with the swinging doors in an open 45 position and shown in fragment;

Fig. 3 is a sectional view taken substantially on the line 3—3 of Fig. 1 with the receptacles or crates omitted; and

Fig. 4 is a fragmentary vertical sectional 50 view taken through the device as herein illustrated.

As disclosed in the accompanying drawings C denotes a cabinet of any desired configuration and dimensions and which affords 55 a substantially inclosed housing, and the

front face of said cabinet is provided with a pair of horizontally swinging doors 2 which are adapted to be maintained in closed position in any desired manner, but preferably through the medium of a conventional 60 type of lock as indicated at 3. The walls and doors 2 of the cabinet are imperforate.

The lower portion of the interior or chamber of the cabinet is intersected by the substantially horizontally disposed shelf S 65 which includes a plurality of separated slats 4 affording openings 5 therebetween through which heated air may pass upwardly through the cabinet for a purpose to be hereinafter more particularly referred to. The compartment A below the shelf S has positioned 70 therein a heating unit U of any desired type and which is caused to burn with a very low flame.

Supported by the shelf S and stacked upon 75 themselves are the receptacles or crates R which substantially entirely fill the compartment B within the cabinet C. The ends 6 of each of the receptacles or crates R are imperforate while the sides and bottom 80 thereof comprise a plurality of separated slats or strips 7 affording openings or spaces 8 therebetween for the circulation of heat.

The forward end 6 of each of the receptacles or crates R is provided with the door 85 9 so that convenient access may be had thereto.

My present invention particularly relates to the preservation of sweet potatoes or other tubers and just after the digging of such 90 potatoes they are placed within the receptacles or crates R and the doors 2 are maintained in open position for a period of between two and three weeks. The doors 2 are then closed and when the seasonal temperature approaches freezing point, the heating unit U is caused to operate. By this means it has been fully demonstrated in actual practice that the sweet potatoes or the like may be preserved for a protracted 95 100 period of time. Attention is particularly directed to the fact that the heating unit U gives off a very low percentage of heat yet this heat, which passes up through the receptacles or crates R, is confined within the 105 cabinet C and effectually serves to prevent freezing of the tubers and to free the same of moisture.

The cabinet C is adapted to be arranged 110 within the kitchen or other room and in

order to facilitate the moving of the cabinet as desired, I provide the same with supporting wheels or casters 10.

In order that the temperature within the cabinet C may be readily determined, I suitably position therein a thermometer T of any ordinary or preferred type.

From the foregoing description it is to be noted that a means for preserving tubers or the like in accordance with my invention is of an extremely simple and comparatively inexpensive nature and is particularly well adapted for use by reason of the convenience and facility with which it may be employed.

15 I claim:

Means for preserving tubers or the like consisting of an inclosed chamber, a shelf intersecting said chamber and provided with

openings, a heating unit positioned within the chamber below the shelf, and receptacles supported upon the shelf and adapted to contain tubers or the like, the sides and bottoms of each of said receptacles being provided with openings, said receptacles being arranged in series, the receptacles of one series being mounted one upon the other, an end of each of the receptacles being provided with a door whereby access to one receptacle may be had independently of the remaining receptacles.

20 In testimony whereof I hereunto affix my signature in the presence of two witnesses.

CORNELIUS T. EVANS.

Witnesses:

W. W. NORRIS,

CLARENCE A. GRINELL.
